CLAIM

The ornamental design for a track propelled small loader, as shown and described.

DESCRIPTION

FIG. 1 is a front perspective view of a track propelled small loader embodying our new design;

FIG. 2 is a top plan view thereof;

FIG. 3 is a front elevational view thereof;

FIG. 4 is a rear elevational view of thereof;

FIG. 5 is a left side elevational view thereof;

FIG. 6 is a right side elevational view thereof; and,

FIG. 7 is a bottom plan view thereof.

1 Claim, 6 Drawing Sheets**OTHER PUBLICATIONS**

Publications by Ramrod Equipment, Taskmaster Loaders, showing models 550, 750, 900, 910 and 944 with attachment pages, a total of 11 pages. Published at least as early as Nov. 1, 2000.

Gravely Skid Steer Loader information, published at least as early as Nov. 1, 2000, 7 pages.

Brochure on TORO DINGO "So What's on This Weekend's Agenda?" published prior to Nov. 1, 2000.
